(57) **CLAIM**

The ornamental design for a slide latch, as shown and described.

DESCRIPTION

FIG. 1 is a top, rear, right perspective view of a slide latch showing our new design;

FIG. 2 is a top, front, right perspective view thereof;

FIG. 3 is a bottom, rear, right perspective view thereof;

FIG. 4 is a bottom, front, right perspective view thereof;

FIG. 5 is a rear elevational view thereof;

FIG. 6 is a front elevational view thereof;

FIG. 7 is a top plan view thereof;

FIG. 8 is a bottom plan view thereof;

FIG. 9 is a right side elevational view thereof;

FIG. 10 is a left side elevational view thereof;

FIG. 11 is a top, front, left perspective of a second embodiment of a slide latch;

FIG. 12 is a top, rear, left perspective view of FIG. 11;

FIG. 13 is a bottom, front, left perspective view of FIG. 11;

FIG. 14 is a bottom, rear, left perspective view of FIG. 11;

FIG. 15 is a rear elevational view of FIG. 11;

FIG. 16 is a front elevational view of FIG. 11;

FIG. 17 is a top plan view of FIG. 11;

FIG. 18 is a bottom plan view of FIG. 11;

FIG. 19 is a right elevational view of FIG. 11; and,

FIG. 20 is a left side elevational view of FIG. 11.

The broken lines illustrate unclaimed portions of the claimed design and environment and form no part of the claimed design.

1 Claim, 10 Drawing Sheets
